CLAIM

The ornamental design for a printer for a computer, as shown and described.

DESCRIPTION

FIG. 1 is a top, front and left perspective view of a printer for a computer showing our new design;

FIG. 2 is a front elevational view thereof with the paper tray removed;

FIG. 3 is a rear elevational view thereof;

FIG. 4 is a top plan view thereof with the paper tray removed;

FIG. 5 is a bottom plan view thereof with the paper tray removed;

FIG. 6 is a right elevational view thereof with the paper tray removed;

FIG. 7 is a left elevational view thereof with the paper tray removed; and,

FIG. 8 is a sectional view thereof taken along line A—A of FIG. 2.

FIG. 1

FIG. 2

FIG. 3

FIG.4

FIG.5

FIG. 6

FIG. 7

FIG. 8
